UNITED STATES PATENT OFFICE.

HIRAM STEVENS MAXIM, OF LONDON, ENGLAND.

RECOVERING SOLVENTS FROM EXPLOSIVES.

SPECIFICATION forming part of Letters Patent No. 430,215, dated June 17, 1890.

Application filed March 4, 1890. Serial No. 342,644. (No model.) Patented in England December 20, 1888, No. 18,663.

To all whom it may concern:

Be it known that I, HIRAM STEVENS MAXIM, mechanical engineer, a citizen of the United States, and a resident of London, England, have invented new and useful Improvements 5 Relating to the Manufacture of Explosives and to Apparatus therefor, (for which I have obtained a patent in Great Britain, No. 18,663, bearing date December 20, 1888,) of which the following is a specification, reference being had to the accompanying drawing.

My invention relates to the manufacture of explosives and to apparatus therefor.

In the production of explosive material by 15 the treatment of gun-cotton with a solvent—such as acetone, ethylic acetate, ether, or the like—considerable loss of the solvent generally occurs in the drying of the product, thus generally enhancing the cost of manufacture 20 of the explosive material.

The object of my present invention is to provide for the recovery of the whole or nearly the whole of the solvents used in the manufacture of such explosive material, and 25 which in the drying of the said explosive material as heretofore practiced are evaporated and lost; and my said invention comprises an improved method of treating the pyroxyline or dissolved gun-cotton for this purpose.

30 My said invention also comprises improved apparatus hereinafter described.

According to my method of recovering the said solvents, I cause heated air or other gas to pass over or in contact with the surface of 35 the dissolved gun-cotton in a drying-chamber or evaporator, so that as the solvents are evaporated they are taken up or absorbed by the air or other gas, and I then conduct the air or other gas carrying the volatilized solvents 40 to a cold chamber or condenser, in which the said solvents condense and from which they may be drawn off in a liquid state. I then reheat the air or other gas passing from the cold chamber and again cause it to pass 45 through the drying-chamber or evaporator, the air or other gas being thus caused to circulate continuously through the entire apparatus.

I have shown in vertical longitudinal central section in the accompanying drawing the apparatus for carrying out this invention.

A is the drying-chamber or evaporator, in

which are arranged a series of pans or trays B B' of any suitable shape, and preferably arranged as shown—that is to say, the said 55 pans B B' are arranged one above another and extend alternately from either side or end of the chamber A to within a short distance from the opposite side or end thereof, so that the air and vapor passing through the 60 said chamber must follow a circuitous path.

C is the cold chamber or condenser, with which the upper end of the drying-chamber or evaporator A is connected by pipes D D' for the passage of the vaporized solvents. 65 The cold chamber or condenser C is connected by a pipe E with a heater F, for heating the air during its return to the drying or evaporating chamber A, with the lower end of which the said heater is connected by a pipe G. The 70 cold chamber C is placed in a tank or vessel H, through which water or other cooling-liquid is caused to flow. The said cold chamber is provided with a discharge-pipe J, having a stop-cock J', beneath which a bottle or other 75 receptacle K may be placed for the reception of the liquid solvent discharged from the said chamber. A fan-blower L, or other suitable apparatus, is provided for causing the continuous circulation of the air through the drying-chamber, the cold chamber or condenser, and 80 the heater.

A small pipe a is provided above each of the pans B B', for the introduction of the pyroxyline or explosive material into the said 85 pans. These pipes a may communicate with a larger pipe or main, suitable cocks being provided where necessary. The cold chamber or condenser C is preferably constructed with a series of small tubes C', to increase the 90 area or amount of cooling-surface.

The operation of the apparatus above described is as follows, viz: The pans or trays B B' being charged with pyroxyline, the fan L is started and the air circulated through 95 the apparatus. The air is warmed in passing through the heater F and ascends between the pans B B' in the drying-chamber or evaporator A, and absorbs or takes up a large quantity of the vapor of the solvent or solvents 100 contained in the said pans. The air is then discharged into the cold chamber C, wherein the solvents condense and fall into the bottle or receptacle K. The air freed from the va-

porized solvents is again passed through the heater F and evaporator A, and so on. By the operation above described the whole or nearly the whole of the solvent or solvents which would otherwise be lost is recovered. The said solvent or solvents may thus be used and recovered a great number of times.

One great advantage arising from the employment of a current of heated air, as above described, is that the evaporation proceeds without the formation of bubbles, such as would be formed if the material were directly heated sufficiently to cause the solvent or solvents to evaporate at the normal pressure of the atmosphere.

I sometimes provide, in combination with the pipe G, one or more chambers M, containing hygroscopic material—such as calcium chloride—through which the air will pass in its circulation through the apparatus, and whereby all the aqueous vapor will be removed from the air, so that the liquid which falls into the bottle or other receptacle K will be free from water, and the explosive material which is being dried will not undergo any change—such as having its surface whitened—as is the case when dried in presence of moisture, but will be transparent and very homogeneous.

The pans or trays in the chamber A are removable. They are preferably arranged in such a manner that they may be lifted out all together. I prefer to make the pans, or, at least, the bottoms of the same, of glass or similar material.

The drying-chamber or evaporator A and the heater F should be inclosed in casings of wood or other suitable material, as shown. The heater F is provided with a coil F', through which steam, hot water, or other heating medium is to be passed.

What I claim is—

The herein-described method of recovering solvents used in the manufacture of explosive material, which consists in exposing the dissolved material in receptacles in a drying-chamber or evaporator and maintaining a constant circulation of air or gas through said evaporator, and a condensing-chamber in communication therewith, heating said air or gas before it enters the evaporator, as set forth.

In testimony whereof I have hereunto signed my name in the presence of two subscribing witnesses.

HIRAM STEVENS MAXIM.
